UNITED STATES PATENT OFFICE

2,039,597

PARACHUTE TOY

Jalmar Juhlin, Milwaukee, Wis.

Application December 12, 1934, Serial No. 757,203

3 Claims. (Cl. 46—86)

This invention relates to toy parachutes and more particularly to a type of parachute that may be tossed into the air a considerable distance before it unfolds.

5 The object of my invention is to provide a toy parachute that may be folded into a very compact arrangement prior to being tossed into the air.

Another object of the invention is to provide a method of retaining the compact arrangement 10 of the parachute while being tossed into the air and designed to disengage quickly and at the proper moment causing the parachute to unfold in its downward path.

Other and further objects of my invention will 15 become readily apparent to persons skilled in the art, from a consideration of the following description when taken in conjunction with the drawing, wherein

Fig. 1 shows a perspective view of the parachute 20 assembly complete in its open position, and

Fig. 2 shows a perspective view of the parachute in its folded position prior to being tossed into the air.

Similar characters of reference indicate corresponding parts in both views and referring to the same, character 10 indicates the spreading portion of the parachute which is constructed of a light textile material, preferably silk or the like, there are threads 11, fastened to the portion 25 10, at 12, and supporting a cylindrically shaped member 15, by means of fastenings at 16, this member 15, is constructed of a pliable resilient material, such as rubber or the like, that may be readily folded or rolled into a flat position and 30 35 when released will again assume its original contour and shape. There is a flat ribbon like band 13, of any convenient length made of a textile material, attached on one end at 14, to the member 15.

40 In operation the entire spreaded portion 10, of the parachute together with the threads 11, are folded and compressed and the member 15, is flattened and wound around the folded parts, the band 13, fastened at 14, on the member 15, is

wound around the entire arrangement and as the unit is tossed or thrown into the air and having reached its extreme height the ribbon 13, will unwind the member 15, and spring into its original cylindrical shape and the weight of the falling 5 member 15, will have a tendency to spread the portion 10, causing the entire unit to slowly descend while being carried along by the air currents, for the amusement of the person causing same to be thrown.

10 It is understood that this entire assembly may be thrown into the air by hand, catapulted by means of a spring actuated device, or by means of any other type of throwing medium and that I am not attempting to set forth forms or modes 15 by which this operation may be accomplished.

In the chosen embodiments of my invention, exemplified by the accompanying drawing, there are present certain novel refinements and improvements, not heretofore disclosed in the prior 20 art, and which will be hereinafter more fully referred to and specifically pointed out in the appended claims.

Having thus described my invention, what I 25 claim and desire to secure by Letters Patent in the United States, is:

1. A toy comprising a parachute member attached to a tubular resilient member equipped with a band disposed to hold the unit in a folded position when the resilient tubular member encircles the parachute member.

2. An aerial toy comprising a parachute member attached to a weighted resilient tubular member disposed to encircle the unit, and a band employed to retain the entire unit in a folded position until released through pressure exerted by the resilient member.

3. In an aerial toy, the combination of a parachute member, a resilient tubular member fastened thereto, disposed to encircle the folded 40 parachute member, and means for temporarily retaining the entire unit in a folded position while being tossed into the air.

JALMAR JUHLIN.
